UNITED STATES PATENT OFFICE.

JESSIE WADE, OF WEST KENSINGTON, LONDON, ENGLAND, ASSIGNOR OF ONE-HALF TO
OLIVER PRESCOTT MacFARLANE, OF LONDON, ENGLAND.

MUSICAL INSTRUMENT.

1,324,530.

Specification of Letters Patent.

Patented Dec. 9, 1919.

Application filed March 19, 1918. Serial No. 223,350.

To all whom it may concern:

Be it known that I, JESSIE WADE, a subject of the King of Great Britain, residing at 22 Girdler's road, West Kensington, London, England, have invented new and useful Improvements in Musical Instruments, of which the following is a specification.

My invention relates to improvements in piano-players and player-pianos of the kind 10 in which a tune sheet passes over a tracker board and controls pneumatic playing mechanism.

Folding tune sheets for automatic musical instruments have been known and the present invention consists in improved means 15 for using tune sheets of this type in instruments of the kind first referred to.

According to my invention I arrange the instrument with a pair of receptacles, one 20 above and the other below the tracker, the folded sheet, when it is to be used, being introduced into the upper receptacle and then drawn between a pair of guide and feed-rollers beneath the tracker and thence into 25 the lower receptacle, in which, as it is drawn by the feed-rollers, it is refolded in zig-zag folds, this being continued until the complete piece has been played. Suitable means are provided for placing the necessary tension 30 upon the sheet in order to insure that it runs evenly and maintains efficient contact with the tracker. For this purpose I may make use of a weight of suitable shape and mass which is placed, or bears, on the music- 35 sheet immediately above and behind the tracker. This tension weight and the feed-rollers are so hinged or otherwise arranged that they can be lifted or moved to permit of the music-sheet being introduced into, 40 and removed from, the appliance and also to enable the sheet to be shifted either backward or forward without the necessity of playing the piano.

Furthermore, the upper receptacle into 45 which the folded music-sheet is introduced when it is to be played is advantageously provided with a cover or the like so arranged that it exerts an adequate pressure or guidance upon the topmost fold of the 50 sheet in order that the said sheet shall be drawn evenly from the receptacle.

To enable the invention to be fully under-

stood I will describe it by reference to the accompanying drawing, in which:—

Figure 1 is a front view of part of a 55 piano-player or player-piano having my improvements applied thereto.

Fig. 2 is a vertical section on the line 2—2, Fig. 1.

a indicates the case of the instrument and 60 *b* is the tracker. *c* is the receptacle which is arranged above and behind the tracker *b*, and *d* is the second receptacle which is located beneath the said tracker. These two receptacles serve, as above described, to receive 65 the music-sheet *e* respectively before and after it is played. The said music-sheet is, as illustrated in Fig. 2, made with transverse creases *e*¹ so that it can be folded in a zig-zag manner and to facilitate the manipulation of the sheet the end sections are 70 advantageously made of a stiffer material such as cardboard.

f and *g* are the guide and feed-rollers which are rotatably mounted in bearings beneath the tracker *b*. The roller *f* is driven from the player mechanism and the music-sheet is gripped between the said roller and the roller *g* with sufficient friction to cause it to be fed from the upper receptacle *c* into 75 the lower receptacle *d*. To permit of the introduction and removal of the music-sheet the guide-roller *g* is made detachable, for which purpose it is provided at its end with pivot pins *g*¹ which engage in slotted bearing brackets *h*. In practice the rollers *f* and *g* are, as shown, arranged with the line joining their centers at an inclination to the horizontal the said rollers being also displaced laterally with respect to the tracker, 80 the object being to insure that the music-sheet is drawn through the rollers in such a direction that it automatically folds in the manner indicated.

i is a roller or weight which is designed 85 to impart the necessary tension to the music-sheet *e*. This roller *i* is rotatably carried in a cradle *j* which is arranged on the top of the tracker *b*, and the sides *j*¹ of which are separated by a distance equal to the 100 width of the music-sheet. The music-sheet, on passing from the upper receptacle *c* is carried below the roller *i* before it reaches the tracker *b* so that the weight of the said

roller operates to give the requisite tension to the music-sheet. The roller is arranged so that it can easily be removed from the cradle *j* in order to permit of the introduction and removal of a music-sheet, and for this purpose any convenient device may be made use of, such as the retaining lugs *k* shown in the drawing.

In practice it is necessary that the position of the music-sheet shall be adjusted relatively to the tracker, and to enable this to be done I provide means whereby the cradle *j* can be adjusted laterally on the tracker. To this end one extremity of the cradle *j* has bearing against it the adjusting screw *l* against which the said cradle is caused to press by means of the spring *m* applied against its other end. As will be obvious, by turning the adjusting screw *l* the position of the cradle, and consequently of the music-sheet, can be adjusted relatively to the tracker *b*.

The upper receptacle *c* is arranged with a cover *c'* which is hinged at *c''* so that it can be raised to permit of the introduction and removal of the folded music-sheet. When the said cover is lowered on to the receptacle, as is illustrated in Figs. 1 and 2, a space or slot *n* is left at the front of the receptacle through which the music-sheet issues, and this slot may, in practice, be so adjusted that it effects a convenient guidance or control on the topmost fold of the sheet to insure that it shall be drawn evenly from the receptacle.

The apparatus operates as follows, that is to say, when a piece is to be played, the music-sheet *e* consisting of the superposed layers, is introduced into the upper receptacle and the topmost layer is drawn out sufficiently to permit it to be placed into the lower receptacle *d*. The tension roller *i* and the guide roller *g*, are then placed in position and the instrument is put into motion whereby the feed-roller *f* draws the sheet *e* from the upper receptacle *c* beneath the tension roller *i* over the tracker *b* and between the rollers *f*, *g*, the said sheet, as it reaches the lower receptacle *d*, refolding itself in a zig-zag manner so as again to form a stack of superposed layers, this operation continuing until the complete sheet has been played. The rollers *g* and *i* can then be detached and the music-sheet removed from the instrument.

In the construction shown in the drawing the receptacle *c* is shown arranged in a horizontal position. It can, however, be placed vertically as shown in broken lines at *c*, Fig. 2, or at an inclination to the vertical. Also the lower receptacle *d* instead of being horizontally placed as illustrated may be arranged at an inclination.

The method of folding and feeding perforated music-sheets, as above described,

possesses a number of advantages in practice. In the first place the inconvenience of having to rewind a sheet of music after it has once been played and before the instrument can be further used is entirely obviated and the further advantage is obtained that any piece of music can be commenced at any desired point; for example, in a music-sheet containing a number of songs, any one of such songs can be played without the necessity of first playing the preceding songs. Again, any portion of the music sheet may be returned to the upper receptacle by removing the rollers *i* and *g* and taking the portion desired from the lower receptacle and placing it in the upper. Furthermore, considerably larger music-sheets, can be made use of than is now possible.

Claims:

1. In a musical instrument, the combination with a tracker and a music sheet co-operating with said tracker, of a substantially horizontal support carrying a removable tensioning means adapted to press said music sheet toward the support, a receptacle arranged adjacent said support adapted to house the music sheet and from which the music sheet is fed, a pair of feeding rollers arranged directly beneath the support, one of said rollers being removable to permit the music sheet to be withdrawn without passing between the rollers, and a second receptacle arranged beneath the feeding rollers adapted to receive the sheet as it leaves said rollers. 100

2. In a musical instrument, the combination with a tracker and a folding music sheet co-operating with said tracker, of a substantially horizontal support carrying a removable tensioning means adapted to press said music sheet toward the support, and a pair of sheet feeding rollers arranged beneath the support, the axis of one of said rollers being arranged in a higher plane than the axis of the other roller to facilitate folding of the music sheet, and one of the rollers being removable to permit the sheet to be withdrawn without passing between the rollers. 110

3. In a musical instrument, the combination with a tracker and a music sheet co-operating with said tracker, of a cradle through which the music sheet travels, said cradle including means for engaging the side edges of the sheet, and means for effecting lateral adjustment of said cradle relative to said tracker. 115

4. In an instrument of the kind defined by claim 3, removable tensioning means carried by the cradle and exerting pressure on the music sheet as it travels through the cradle. 125

5. In a musical instrument, the combination with a tracker, of a cradle through which the music sheet travels, said cradle 130

having end walls for engaging and guiding the side edges of the sheet, lugs carried by the end walls of the cradle and projecting toward each other, and a roller weight having its periphery contacting with said lugs and resting on the sheet.

5. In a musical instrument, the combination with a tracker, of a folded music sheet coöperating with said tracker, rollers for

feeding said sheet over the tracker, one of 10 said rollers being removable to permit said sheet to be moved relative to the rollers without being moved thereby, a cradle, and a removable tension device located in said cradle and adapted to engage the music 15 sheet for providing the necessary tension on the sheet.

JESSIE WADE.
